UNITED STATES PATENT OFFICE.

MARSHALL B. PALMER AND CLARK S. MUDGE, OF GERMANTOWN,
NEBRASKA.

PERMUTATION-PADLOCK.

SPECIFICATION forming part of Letters Patent No. 375,505, dated December 27, 1887.

Application filed October 20, 1887. Serial No. 252,889. (No model.)

To all whom it may concern:

Be it known that we, MARSHALL BUR
PALMER and CLARK SALATHIEL MUDGE, of
Germantown, in the county of Seward and
5 State of Nebraska, have invented a new and
Improved Permutation-Padlock, of which the
following is a full, clear, and exact descrip-
tion.

Our invention relates to padlocks, the ob-
ject of the invention being to provide a per-
mutation-lock which shall be of simple con-
struction, but which will be strong, service-
able, and safe in that it cannot be tampered
with by unauthorized parties. These objects
15 we accomplish by means of the novel construc-
tion to be hereinafter described, and specific-
ally pointed out in the claim.

Reference is to be had to the accompanying
drawings, forming a part of this specification,
20 in which similar figures of reference indicate
corresponding parts in all the views.

Figure 1 is a face view of our improved form
of permutation-padlock. Fig. 2 is a similar
view with one of the outer side plates and its
25 connections removed. Fig. 3 is a view of the
inner face of one of the side plates and its con-
nections. Fig. 4 is a perspective view of the
bow or shackle which we employ in connec-
tion with our improved form of lock; and Fig.
30 5 is a central sectional view of the lock, taken
on line *x x* of Fig. 1.

In constructing such a lock as the one forming
the subject-matter of this application we
provide a main frame, 10, the side faces of
35 which are recessed, as shown at 11, to receive
disks 12, that are formed with slots 13, said
slots extending from the peripheral edges of
the disks inward toward the centers thereof.
These disks 12 are rigidly connected to or
40 made integral with central pins or posts, 14,
that are formed with shoulders 15, which
shoulders pass outward through side plates,
16, that are riveted to the frame 10.

Against the shoulders 15 of the pins or posts
45 14 we place washers 17, upon which there are
engraved a series of characters, as shown in
Fig. 1, and upon the outer faces of the side
plates, 16, we engrave or mark another series
50 of characters, 18, which characters are arranged
between dividing-lines 19. The washers 17

are held in place by nuts 20, which are
threaded to engage with threads formed upon
the extending ends of the pins or posts 14.

In addition to the recesses 11 of the frame
10 said frame is provided with a central ver-
tical slot or opening in which there is fitted
the shank 22 of the bow or shackle 50, said
shank 22 being flat, and being provided at its
lower end with shoulders 23, which shoulders,
when the lock is locked, bear against the pe-
ripheral edges of the disks 12. Above the
shank 22 the bow or shackle 50 extends at
right angles thereto, as shown at 24, and from
the end of this extending section 24 the bow
proper extends upward, preferably in a curved
line, and then downward, as in the case of an
ordinary shackle, the end 25 of the curved sec-
tion of the bow being arranged to enter a re-
cess, 26, that is formed in the frame 10.

In setting the lock the bow or shackle 50 is
drawn up to the position indicated by dotted
lines in Fig. 2, and when in this position the
projections below the shoulders 23 of the shank
22 will enter the slots 13 of the disks 12, said
projections thus holding the disks from turn-
ing, so that the washers 17 may, by means of
tongs, pinchers, pliers, or other proper imple-
ment, be turned to bring any desired mark
upon the washers into register with any de-
sired mark upon the side plates of the lock.
The registering characters or marks are then
carefully noted in order that the lock may be
opened after the bow or shackle has been re-
turned to the position in which it is shown in
Figs. 1, 2, and 5; for, by bringing the marks or
characters into register, the slots 13 of the
disks 12 will be brought directly above the
shoulders 23 of the shank 22, and the shackle
may be once more drawn up to the position
indicated by dotted lines in Fig. 2, thus pro-
viding for the introduction or the withdrawal
of a staple within or from the curved section
of the bow or shackle.

Although any number of characters might
be engraved upon the washers 17, we find it
convenient in practice to provide said washers
with fifteen characters; and, although any
number of characters might be engraved upon
the plates 16, we prefer to provide said plates
with sixteen characters, that are separated by

graduating lines or marks, as indicated in Fig. 1.

With such a lock as the one above described it will be almost impossible for an intruder to open the lock unless the combination of both washers and plates is known to him.

Having thus fully described our invention, we claim as new and desire to secure by Letters Patent—

10. In a permutation padlock, the combination with a main frame formed with recesses 11 and a central longitudinal slot, of disks 12, which fit within the recesses 11, said disks being formed with slots 13, pins or studs 14, 15 extending outward from the disks and formed with shoulders 15, character-bearing plates 16,

that are connected to the frame and through which pins or studs extend, character-bearing washers 17, nuts 20, which hold the washers against the shoulders 15, and a bow or shackle, 20 25 50, formed with a shank, 22, at the lower end of which there are shoulders 23, said shank being fitted within the central slot of the main frame of the lock, while the end of the curved section of the bow is arranged to enter a recess formed in the main frame, substantially as described.
